UNITED STATES PATENT OFFICE.

MATTHEW O'FARRELL, OF DETROIT, MICHIGAN, ASSIGNOR TO CHICAGO PNEUMATIC TOOL COMPANY, OF NEW YORK, N. Y., A CORPORATION OF NEW JERSEY.

DRILL AND MANUAL SUPPORT THEREFOR.

Application filed December 8, 1925. Serial No. 73,997.

This invention relates to drilling machines and to arrangement for manually supporting the same. It is particularly concerned with machines of the percussive type used in mining, quarrying and similar operations and commonly referred to as rock drills.

In using rock drills it is frequently necessary to change from cradle or shell mounted machines to manually supported machines. 10 In order that two sets of drills may not be required it is essential that the cradle supported drill be capable of having a handle device attached thereto which will enable the drill to be manually directed. Hence one 15 object of the invention is to provide a drilling machine of the type described arranged to have a handle device readily attached thereto or detached therefrom at will. Another object is to so design the drill and handle device that the application and the removal of the latter will not necessitate disturbing the assembly of the drilling machine. Another 20 object is to relieve the manual supporter of the machine of the shocks and vibrations incident to the operation of the machine. Further objects relate generally to simplifying and to improving prior structures devised for similar purposes.

In order to illustrate the invention one concrete embodiment thereof is shown in the accompanying drawing in which the single view is a front elevation of a percussive drilling machine.

In the embodiment of the invention chosen 35 for the purpose of illustration the percussive drill which may be of the fluid pressure type comprises a cylinder having a back head 2 and front head 3 these parts being maintained in assembled relation by the usual side bolts 40 4 which may seat in guides 1^a on cylinder 1.

To permit a handle device to be readily secured to the drill the rear and front heads, 2 and 3, are provided with extensions 2^a and 3^a respectively having aligned openings 2^b and 3^b respectively. The handle device is formed 45 with a grip portion 5 having spaced rods 6 extending therefrom and arranged to extend through the aligned guide openings 2^b and 3^b of the rear and front heads of the drill. 50 Suitable means, such as springs, are arranged to engage stops on the handle device and adjacent portions of the machine in order to absorb the shocks and vibration produced by the latter. A preferred arrangement for this 55 purpose is illustrated in the drawing wherein

coiled springs 8 are mounted on the handle rods 6 on opposite sides of collars 9 which may be fixed to rods 6 in any suitable manner as by pins 10. The outer ends of the springs thus engage the projecting portions 3^a and 2^a of the front and back heads. In this manner the handle device is normally maintained in the position which permits maximum relative movement in a forward direction. When the operator presses the tool to 60 the work, nuts 7 on rods 6 are extended out of contact with lugs 3^b. This brings all of springs 8 into operation with the result that they absorb to a large extent, if not entirely, the vibration, shocks and reaction of the drill 65 which are ordinarily communicated directly to the operator.

In assembling the handle device upon the drill it is apparent that it is entirely unnecessary to disturb the drilling machine itself 75 or to disconnect any parts thereof. The rods 6 of the handle device are first inserted through the openings 2^b in the lateral extensions 2^a of back head 2. The rearward springs 8 are first slipped over rods 6 after 80 the same have passed through the back head. Then the collars 9 are applied and then the forward springs 8. The threaded outer ends of the rod 6 are then pushed through the openings 3^b in the lateral extensions 3^a of the 85 front head 3 and the stop nuts 7 are applied. The collars 9 are then fixed in position upon rod 6 by inserting pins 10 and the drilling machine is ready for use as a hand supported tool. The handle device is as readily removed from the drilling machine by reversing 90 the steps of the process above outlined.

While but one form of the invention has been herein shown and described, it is to be understood that the invention is not limited 95 to such specific details but covers all changes, modifications and adaptations within the scope of the appended claims.

I claim:

1. In combination, a drill having a cylinder, front and back heads, and side bolts securing said parts in assembled relation, a handle device comprising a grip part and spaced rods extending therefrom, said heads being provided with guide openings for said 100 rods, means for preventing withdrawal of said rods from said openings but permitting limited movement of the same therein, and means on said rods between said heads for 105 yieldingly resisting such movement.

2. In combination, a drill having a cylinder, front and back heads, and side bolts securing said parts in assembled relation, a handle device comprising a grip part and spaced rods extending therefrom, said heads being provided with guide openings for said rods, means for preventing withdrawal of said rods from said openings but permitting limited movement of the same therein, and 10 means including coil springs on said rods in engagement with said heads for yieldingly resisting such movement.

3. In combination, a drill having a cylinder, front and back heads, and side bolts 15 securing said parts in assembled relation, a handle device comprising a grip part and spaced rods extending therefrom, said heads being provided with guide openings for said rods, means for preventing withdrawal of 20 said rods from said openings but permitting limited movement of the same therein, stops on said rods intermediate said heads, and coil springs encircling said rods and confined between said heads and said stops yieldingly 25 to resist relative movement of said handle device.

4. In combination, a drill having a cylinder, front and back heads, and through bolts securing said parts in assembled relation, a 30 handle device comprising a grip part and spaced rods extending therefrom, said heads being provided with guide openings for said

rods permitting relative movement, stop collars fixedly secured to said rods intermediate said front and back heads, and coil springs 35 encircling said rods on opposite sides of said collars yieldingly to resist the movement of said handle device.

5. In combination, a drill having a cylinder, front and back heads, through bolts 40 securing said parts in assembled relation, said heads having extensions in the plane of and beyond said side bolts, said extensions having aligned openings, a handle device having rods extending through said aligned openings, 45 and means on said rods intermediate said heads including resilient members in engagement with the latter for cushioning the movements of the drill relative to said handle.

6. In combination, a drill having a cylinder, front and back heads, through bolts 50 securing said parts in assembled relation, said heads having extensions in the plane of and beyond said side bolts, said extensions having aligned openings, a handle device 55 having rods extending through said aligned openings, stop collars fixed to said rods intermediate said heads, and coil springs encircling said rods on opposite sides of said collars for cushioning the movement of said 60 device.

Signed by me at Detroit, Mich., this 4th day of December, 1925.

MATTHEW O'FARRELL.
